UNITED STATES PATENT OFFICE.

ARTHUR T. GOLNIK, OF NEW YORK, N. Y., ASSIGNOR OF ONE-HALF TO EDITH P. WOOD,
OF NEW YORK, N. Y.

DESIGN FOR A TOY CAT.

Application filed February 23, 1924. Serial No. 8,716. Term of patent 3½ years.

To all whom it may concern:

Be it known that I, ARTHUR T. GOLNIK, a citizen of the United States, residing at New York, in the county and State of New York, have invented a new, original, and ornamental Design for Toy Cat, of which the following is a specification, reference being had to the accompanying drawing, forming part thereof, in which—

Figure 1 is a front elevation of the toy, and

Figure 2 is a side elevation thereof.

I claim:

The ornamental design for a toy cat as shown.

ARTHUR T. GOLNIK.
